AUTOMATIC GAIN CONTROL CIRCUIT

Alfons Andreatta, Berlin, Germany, assignor to
General Electric Company, a corporation of
New York

Application May 14, 1938, Serial No. 207,898
In Germany June 25, 1937

3 Claims. (Cl. 250—20)

The present circuit organization serves to insure automatic stabilization of the audio output potential, or power, in a radio frequency apparatus, for instance, of a receiver set, in the presence of fluctuations of the radio potential acting at the input of the apparatus.

The present scheme differs from circuits comprising exponential tubes insofar as the fluctuations of the output potential can be easily kept inside narrow limits, say, ± 20 per cent, whereas in simple circuit arrangements including regulating tubes the resulting fluctuations of the output potential are far greater, say at the ratio of 1:3 or even 1:5. The novel circuit organization here disclosed further offers the merit that a wide range of control is realizable. Inasmuch as for control action itself the audio alternating voltage resulting from rectification is used, the circuit scheme is useful only if the radio potential is modulated.

In the drawing:

Fig. 1 shows a circuit embodying the invention, Fig. 2 shows curves illustrating the action of the control circuit.

Referring to the drawing, 1 denotes the signal input circuit, 2 is a radio amplifier tube. The plate circuit of this tube comprises a coil 3 to which two tuned circuits 4 and 5 are coupled. The radio energy is rectified by the two diodes 6 and 7. Now, arrangements could be made in such a way that the diode 6 cuts off, for instance, the bottom alternations of the radio current by rectification. Incidentally, the coupling of circuit 5 and the polarity of the diode 7 may be so chosen that rectification by diode 7 will cut off the upper alternations of the radio waves. The modulations of the two diodes, as will thus be seen, are of like value, but displaced 180 degrees in phase.

If the two potentials arising across the resistances 8 and 9 are impressed upon a common resistance, say the grid leak 10' of tube 11, there results an audio potential whose sum total is zero. However, zero voltage results only in the presence of perfect symmetry of the circuit organization. What is of interest here is lack of symmetry for which the constituent potentials are of dissimilar size. In such a case the sum voltage is of a value other than zero, and the curve-shape of the same will correspond exactly to the modulation voltage at the grid of tube 2. The higher the radio potential at the tube 2, the higher will be the voltages across the resistances 8 and 9. If, then, care be taken so that the difference of these voltages stays constant, there will always result the same curve for the differential

potential, regardless of what value the incident radio potential may be. In other words, if the differential potential preserves its uniform and stable time-shape, this fact will insure a perfectly automatic voltage regulation. At the grid 5 of tube 11 arises a constant potential, and in the plate circuit of this tube, therefore, a constant output power, regardless of the size of the incident signal energy.

The lack of symmetry of the circuits which is 10 required for the stabilization of the regulating voltage may be realized in various ways. For instance, one diode may be subjected to a biasing potential. Another plan would be to damp one 15 of the diode tuning circuits. Also diodes presenting dissimilar slopes of their characteristic could be used, or the load resistances 8 and 9 could be made of dissimilar size. Finally, the 20 closeness of coupling with the coil 3 of the two circuits 4 and 5 could be made dissimilar. As a 25 general rule, two or more of the said steps are combined more preferably in order that the optimum regulator curve form may be secured.

In the exemplified embodiment here illustrated, the two circuits 4 and 5 are coupled to coil 3 25 equally closely. A difference in the radio potentials is obtained in the two circuits by connecting a damping resistance 12 in parallel relation to the coil 5. Moreover, the diode 7 is impressed from potentiometer 13 with a direct current voltage so 30 as to bias the same. The effect of this biasing voltage is that the regulator curve as shown in Fig. 2 of the drawing initially rises rather rapidly and steeply, and as a result the desired constancy of the output voltage is attained at a fast rate. 35 Fig. 2 shows the regulator curve as obtained by measurement in a circuit organization of the kind shown in Fig. 1. If care is taken so that no phase distortions arise in the novel circuit organization here disclosed, the same scheme will be found 40 useful for automatic volume control in broadcast receiver sets.

What is claimed is:

1. In combination with a modulated carrier amplifier and a modulation amplifier, a demodulation network consisting of two rectifiers each having a carrier input circuit coupled to the carrier amplifier output, said rectifiers being connected in opposition, means for impressing the differential modulation voltage output of said 45 rectifiers upon the input of said modulation amplifier, said rectifiers being constructed and arranged to provide a differential voltage whose value increases with carrier amplitude increase 50 at such a rate as to maintain the modulation 55

amplifier output substantially constant, each of said rectifiers being of the diode type, and one of the diodes having a delay bias applied thereto and a damping resistor being connected in the carrier input circuit of said delayed diode.

2. In combination with a modulated carrier amplifier and a modulation amplifier, a demodulation network consisting of two rectifiers each having a carrier input circuit coupled to the carrier amplifier output, said rectifiers being connected in opposition, means for impressing the differential modulation voltage output of said rectifiers upon the input of said modulation amplifier, said rectifiers being constructed and arranged to provide a differential voltage whose value increases with carrier amplitude increase at such a rate as to maintain the modulation amplifier output substantially constant, and one of said recti-

fiers having its input circuit damped, said one rectifier being of the delayed type.

3. In a modulated carrier energy receiver of the type including at least a carrier amplifier, a demodulator and a modulation voltage amplifier all arranged in cascade; the improvement which includes a second demodulator arranged in cascade between said two amplifiers, means for combining the modulation voltage outputs of the two demodulators in polarity opposition, and one of 10 said demodulators being substantially damped relative to the other demodulator and providing a modulation voltage which is constantly different in magnitude from the modulation voltage output of the other demodulator, and means for 15 applying a delay bias to said one demodulator.
